OF BENLD, ILLINOIS.

BARREL-TAP.

1,096,117.

Specification of Letters Patent.

Patented May 12, 1914.

Application filed August 7, 1913. Serial No. 783,546.

To all whom it may concern:

Be it known that I, JOHN MELISCH, a subject of the Emperor of Austria-Hungary, residing at Benld, in the county of Macoupin and State of Illinois, have invented certain new and useful Improvements in Barrel-Taps, of which the following is a full, clear, and exact description, reference being had to the accompanying drawings, 10 forming a part hereof.

My invention has relation to improvements in barrel taps; and it consists in the novel details of construction more fully set forth in the specification and pointed out 15 in the claim.

In the drawings, Figure 1 is a side elevation of a conventional aerated-beverage dispensing system showing my invention applied thereto; Fig. 2 is an enlarged middle, 20 vertical section through the coupling, the valve being turned to closed position; Fig. 3 is a section on the order of Fig. 2 with valve turned to open position, the upper coupling member being in elevation; Fig. 4 is an elevational detail of the coupled ends of the two sections of the coupling, the valve being turned to closed position; Fig. 5 is a 25 cross-section on the line 5—5 of Fig. 2, the section being limited to the coupling only; Fig. 6 is a section similar to Fig. 5 with valve however turned to open position; Fig. 7 is a vertical middle sectional detail of the upper end of the lower or stationary section of the coupling; Fig. 8 is a cross-section on 30 the line 8—8 of Fig. 4; Fig. 9 is a section similar to Fig. 8, but showing the valve turned to open position; Fig. 10 is a sectional detail on the line 10—10 of Fig. 2, parts being broken; and Fig. 11 is an end 35 view of the inner terminal socket of the outer fitting or coupling-member.

In dispensing aerated beverages such as beer, ale and the like, it is the prevailing custom to drive the intake or supply pipe 45 for the liquid through an opening in the wall (usually the head) of the barrel or cask, each time a fresh cask is tapped. This process is usually attended with more or less loss of the liquor, the latter escaping through 50 the opening before the opening is fully covered or plugged by the entering pipe. To avoid such losses is the main object of my invention. For this purpose I provide each cask or barrel with a feed or supply pipe 55 dipping or reaching to the bottom of the

vessel, such pipe being made a permanent equipment of each cask or barrel, and being provided with a service valve the casing of which is coupled to the lower terminal fitting of the service pipe, which fitting may be readily coupled to said casing from the outside of the cask, without any attendant loss of the liquid. The fitting referred to 60 controls and operates the valve identified with the feed-pipe, the valve-casing and the fitting thus forming two sections of a coupling—here termed for convenience as a valve-coupling—which may be readily assembled or uncoupled, all as will more fully hereinafter appear from a detailed description 65 of the invention which is as follows:

Referring to the drawings, B represents a barrel containing beer (or other liquor) provided with a permanently installed feed-pipe 1 reaching to the bottom of the barrel, 70 and preferably stayed by a terminal pointed plug *a* engaging said bottom. From the barrel leads a flexible (rubber) service pipe P whose upper end is coupled to the refrigerator coil C whose upper end terminates in 75 the usual dispensing faucet F in the bar-room. With the exception of the member 1, the parts referred to are well understood in the art and require no detailed description.

To the upper end of the pipe 1 is screwed 80 a hollow shell or chambered head 2 whose upper portion is interiorly screw-threaded (Fig. 3), said portion receiving a disk 3 provided with diametrically opposite ports or openings *o*, *o*, said disk serving as a seat 85 for the rotatable disk-valve V likewise provided with diametrically opposite ports *o'*, *o'*, registerable with the ports *o*, *o*, a ported packing ring or washer *w* secured to the valve being interposed between the valve 90 and the seat 3. The upper face of the valve is provided with a diamond-shaped (or equivalent polygonal) head 4 by which the valve may be rotated. The disk 3 is preferably secured or coupled by means of pins 95 *p*, *p*, to the adjacent end of the chambered screw-plug or valve-casing 5 terminating in a flange or head 5', the said plug or valve-casing (with its head) being screwed into 100 the head of the barrel and driven flush with the same (Fig. 3), the lower end of the plug with the disk 3 entering the shell 2 at the upper end of the pipe 1 previously installed in the barrel. A clearance or space *h* is left 105 below the head 5' around the plug-body 5 110

as shown to best advantage in Fig. 3. The bottom of the disk-valve V is provided with a central depending stem or spindle 6 loosely received by the seat 3, a nut n passed over the lower screw-threaded end of the stem retaining the valve to its seat. The rotations imparted to the valve V are limited in either direction by a screw or plug 7 projecting radially from the periphery of the valve and operating in and through the peripheral registering slots s, s' of the plug 5 and shell 2 respectively. As shown, the part 2 being of greater diameter than the bung-hole, it would be necessary to first screw the part 5 into the barrel head and attach to it the parts 1, 2, and 7, during the process of making the barrel; but in practice the bung-hole should be made large enough to admit of the insertion or removal of the assembled parts at any time.

The member 5, 5', with the shell 2 coupled thereto (and forming with the pipe 1 a permanent installation for each barrel or cask) may be considered as the lower stationary section or member of the coupling to which the present invention is directed, said lower member carrying the service-valve V. This valve is actuated by what may be termed as the upper detachable and rotatable section or member of the coupling, said upper section being provided with means for actuating the valve, and with means by which a coupling between the two sections may be effected.

The upper section or member of the coupling comprises a tubular fitting or pipe 8 having leading therefrom a branch 8' terminating in a screw-plug 9 to which a hose 10 leading from any convenient source of compressed air supply such as an air pump or its equivalent (not shown) may be coupled, the inner end of the plug terminating in a rubber check-valve m well understood in the art. To the upper end of the fitting 8 is secured a transversely peripherally ribbed or grooved stem 11 to which the service hose or pipe P may be attached. Inserted in the pipe fitting 8 and preferably shouldered thereto, is an inner pipe-section or sleeve 12 around whose upper end is a packing-ring 13, the said sleeve spanning the opening at the inner end of the branch 8', and being provided opposite and facing said opening, with a longitudinal peripheral groove e, said groove thus forming a passage-way between the sleeve and inner wall of the member 8, which passage-way terminates at the bottom in a radial port or passage e' formed in the basal portion of the member, the outer terminal of said passage being adapted to be brought into register with an outlet port e'' in the wall of the plug 5 and normally closed by a plug or wiper 14 at the free end of a flexed arcuate spring or arm 15 having its fixed end secured to the member 5 along the

outer wall thereof. It may be stated in passing that the outer portion of the port or passage e' traverses one of the peripheral lugs or processes 16, 16, formed on the member 8 for a purpose to be now described. It will be seen that there are disposed in the head 5' of the member 5 at points diametrically opposite one another two recesses 17, 17, from the bottoms of which there lead in opposite directions along the inner walls of said head suitable grooves 18, 18, each covering an arc of something over ninety degrees (Figs. 5, 6, 10). Now, at the base of the fitting 8 are formed diametrically opposite one another the lugs or processes 16 which are free to enter the recesses 17, and which after they have reached the bottoms of said recess are free to enter the grooves 18, this being accomplished by simply giving the member 8 sufficient rotation to cause the lugs to enter said grooves. This done, the member 8 becomes coupled to the fixed member 5; and it is when the rotation of the member 8 is effected to bring about the coupling of the members that the port e' is brought opposite the port e'' in the plug 5. In the rotation of the member 8 to bring the port e' opposite the port e'', the rounded side of the lug 16 dislodges the head 14 normally closing the port e'', thus uncovering said port and establishing free communication therethrough between the port e' and a passage or port t leading from the annular space h. It may be stated that the purpose of the head 14 carried by the flexed spring 15 is to keep clean the port e'' so that there will be no clogging thereof by dirt, and hence for a coupled position of the members 5 and 8, the air employed to drive the beer out of the barrel will have free passage from its supply source into the barrel above the beer. The lower end of the member 8 terminates in a diamond-shaped socket 19 free to pass over the head 4 of the valve V when the member 8 is first inserted into the member 5, the member 8 being provided with ports or peripheral openings i for the flow of the liquor into the tube 12 after passing the valve V. When the member 8 is fully inserted the socket 19 will have been passed over the head 4 of the valve, the shoulder 20 with its packing ring 21 at the base of the reduced terminal in which the socket 19 is formed, resting on the annular ledge 22 of the plug 5 (Fig. 3). The bottom of the pipe 1 is provided with peripheral intake openings f.

The operation of the device is substantially as follows:—It has already been stated that the member 5 (5') with its shell 2 and intake or supply-pipe 1 is a permanent installation for the barrel B. When a fresh barrel is to be tapped, the bar attendant or helper seizes the fitting 8 and inserts the lugs or formations 16, 16, thereof

through the recesses 17, 17, (Figs. 2, 10) until the lugs come opposite the grooves 18, 18. In this insertion the socket 19 passes over the head 4 of the valve V, and the operator by then giving the fitting 8 a turn (clockwise, Fig. 10) will cause the lugs 16 to traverse the grooves 18, 18, and since these grooves incline slightly from the bases of the recesses 17 (Fig. 7), the lugs will be tightly wedged therein by reason of the compression of the elastic washer 21 (the compression resulting from the lugs following the inclined grooves 18 and hence squeezing the washer against the ledge 22). The turning of the fitting 8 is permitted even with the hose P and 10 attached thereto because the hose are flexible and the slight turn imparted to the member 8 does not exert an excessive strain on the hose. With the turning of the member 8 as indicated, the lugs 16, 16, pass from the position shown in Fig. 5 to that shown in Fig. 6, that is to say, the lug on the right dislodges or lifts the head 14 carried by the spring 15, uncovering the opening e'' : but since in this rotation of the member 8 the port e' (forming a continuation of the passage e) is brought into register with the port e'' , it follows that the compressed air (or other gas) is free to flow from the hose 10, through the passage e (Fig. 3) thence through ports e' , e'' , into port t , and into the barrel on top of the beer. At the same time (with the turning of the member 8) the head 4 of the valve V will have been turned (Figs. 6, 9) to rotate the valve to bring the ports o' , o' , thereof into register with the ports o , o , of the valve-seat 3, allowing the liquid or beer (subjected to the pressure of the air in the barrel) to be expelled from the barrel through the openings f , pipe 1, shell 2, ports o , o' , ports i , tube 12, fitting 8, hose or pipe P, coil C, to the faucet F. By opening the faucet F, the beer may be served. Should it be desired at any time to close the valve V, the attendant simply turns the fitting 8 back to a position to bring the lugs 16 opposite the recesses 17, this having the effect of turning the ports o' out of register with the ports o , whereupon not only will the beer be cut off from escape from the barrel, but the driving gas or compressed air will be cut off, the port e' being brought out of register with the port e'' (Fig. 5). In a fresh barrel, the valve V occupies the position shown in Figs. 2, 5, 8; in a barrel in service the valve V occupies the position shown in Figs. 3, 6, 9. In other words, the valve is not open until the connection between the two sections of

the coupling is complete. Since each barrel is equipped with a member corresponding to the fixed or stationary section of the coupling, it is apparent that all that is necessary to "tap" a barrel is to couple thereto 65 the fitting 8 in the manner described, and the connection is completed.

No loss of liquor or beverage can follow from the use of the present invention.

Having described my invention, what I 70 claim is:—

In combination with a vessel containing liquid, a pipe dipping beneath the surface of the liquid in the vessel and having openings to receive the liquid, a terminal tubular valve-casing at the upper end of the pipe accessible from the outside of the vessel, the casing being provided with recesses along the bore of the casing, grooves leading from the recesses in opposite directions, 75 a tubular rotatable fitting having lugs insertible into the recesses and adapted to traverse the grooves, a rotatable ported valve in the casing, a polygonal central head on the valve, a socket on the fitting adapted to engage the head with an insertion of the lugs into the recesses aforesaid, the fitting being provided with a liquid passage-way leading from the socket aforesaid, 80 said passage-way communicating with the chamber of the valve-casing at a point above the socket and open at the opposite end for discharging the liquid, a gas passage-way contiguous to the liquid passage, a source of compressed air supply communicating 85 with said gas-passage-way, the latter discharging through one of the lugs aforesaid, a port in the wall of the valve casing adapted to be brought into register with the passage-way in the lug with a rotation of the 100 fitting, a spring-controlled plug normally closing said port and adapted to be dislodged by the ported lug, a port in the vessel wall leading from the port controlled by said plug and leading to the space in 105 the vessel above the liquid, communication between the liquid in the vessel and the liquid-discharge end of the fitting, and between the compressed air supply source and the interior of the vessel being established 110 with a rotation of the fitting and valve through an arc sufficient to uncover the valve-ports.

In testimony whereof I affix my signature, in presence of two witnesses.

JOHN MELISCH.
